[57] ABSTRACT

A signal switching device with a plurality of each of first and second groups of rectangular parallelopiped switching units arranged in X, Y, and Z directions. A plurality of first groups of spaced parallel conductors are disposed in said X direction in respective spaced X-Z planes of said first group units for multiply connecting of break terminals of corresponding switches in said respective first group unit stacks. A plurality of second groups of spaced parallel conductors are disposed in said Y direction in respective Y-Z planes for multiply connecting make terminals of corresponding switches of said second group units in said Y-Z planes. Input signal lines are disposed in parallel and connected to break terminals of said switches in respective first group units in said X-Z planes, while output signal lines are disposed in parallel and selectively connected to make terminals of switches of the second group units in the Y-Z planes, whereby a desired one of the input lines is connectable to a desired one of said output lines.

SIGNAL SWITCHING DEVICE

This invention relates to signal switching devices of the kind for establishing connections, for example, between one of a plurality of inlets and one of a plurality of outlets. This invention admits of suitable application with electronic computers, data or information processing equipment, information switching equipment, and the like.

In conventional signal switching devices wherein signal transmission paths are selectively established, it is desirable that the number of switching elements included therein be kept to a minimum. To fulfill this purpose, it has been common to provide a plurality of input signal lines, hereinafter inlets, and a plurality of output signal lines, hereinafter outlets, disposed so as to orthogonally intersect each other and to provide a plurality of signal switching matrices, each having its basic unit comprised of switching elements capable of bridging across an inlet and an outlet at each intersecting crosspoint, which matrices are interconnected in linkage form. Stated more specifically, switching stages, each containing a plurality of signal switching matrices, may comprise a primary switching stage to which the inlets are connected, a plurality of intermediate switching stages, and a final switching stage to which the outlets are connected, all stages being interconnected in linkage form.

The switching capacity of each signal switching matrix, which may comprise a crossbar switch, is limited by the predetermined numbers of inlets and outlets included therein. The provision of only a few predetermined kinds of matrices differing in capacity, even though the matrices are suitably combined, does not result in an economical structure containing a minimum number of crosspoints or switching elements. In other words, conventional switching matrix designs lack sufficient versatility for constructing signal switching devices therefrom having varying capacities. Conversely, the preparation of many individual kinds of signal switching matrices is not preferred because the benefits that were formerly derived from the mass production of fewer kinds of components are sacrificed. Furthermore, since linkage connections between two signal switching matrices invariably produce points of intersection, mechanical or automatic wiring cannot be adopted and therefore, manual soldering or wrapping work must be utilized to execute the vast number of requisite wiring operations. This results in low manufacturing efficiencies and high manufacturing costs. In addition, since the linkage connections intersect one another, linkage wires tended to become long, and crosstalk of switched information signals is increased. Therefore, conventional devices comprised of such matrices are not suitable for operating on signals containing comparatively high frequency components, such as video signals.

Therefore it is an object of this invention to provide a most economical signal switching device comprised of segments of the same geometry, said segment being the basic unit of the device irrespective of the device switching capacity.

Another object of the invention is to provide a most economical signal switching device comprised of a plurality of segments of the same geometry and having a minimum number of switching elements.

Still another object of this invention is to provide a signal switching device wherein linkage connections do not include points of intersection in any plane.

An additional object of this invention is to provide a signal switching device that admits of facile manufacture and may be produced by automatic fabricating techniques.

A further object of the invention is to provide a broad-band signal switching device with as small cross-talk attenuation as possible.

According to this invention, l , m , and n segments (l , m , and n each being a positive integer equal to or larger than unity), each segment comprising P (P being a positive integer equal to or larger than unity) signal switching elements, are disposed successively along the X, Y, and Z rectangular coordinate axes so as to form a three-dimensional array. According to one kind of segment, the terminals of an array of switching elements included therein are disposed in the same direction on each of two spaced parallel surfaces of the segment. In accordance with another kind of segment, the terminals of an array of switching elements included therein are disposed in the same direction on each of two adjacent perpendicular surfaces of the segment. In accordance with still another kind of segment, auxiliary terminals of an array of switching elements included therein are connected to respective terminals disposed on one of the two spaced parallel surfaces of the segment and, in addition, the auxiliary terminals are disposed in the same direction on either surface perpendicular to said two spaced parallel surfaces. The switching device thus formed includes a input signal lines, hereinafter inlets, (a being a positive integer equal to or larger than 1) each of which inlets may admit of multiple connection with the terminals of an array of switching elements included in a segment, said a inlets being disposed, for example, in the X direction; b output signal lines, hereinafter outlets (b being a positive integer equal to or larger than 1), each of which outlets may admit of multiple connection with the terminals of an array of switching elements included in a segment, said b outlets being disposed, for example, in the Y or Z direction; and c interconnection means (c being a positive integer equal to or larger than 1), each of which may admit of multiple interconnection between terminals associated with those terminals of an array of switching elements included in a segment to which the inlets are connected and with terminals associated with those terminals of an array of switching elements included in a segment to which the outlets are connected said interconnection means extend, for example, in the Z or Y direction.

More specifically, the three-dimensional structure of segments as above-mentioned may be regarded as consisting of a plurality of segment groups which are divisible in any one direction, such as, for example, the Z direction, such that, when any two groups to be switched are taken into consideration, the inlets are associated with one group and the outlets are associated with the other group, and linkage wires are connected between the two groups. It thus becomes possible with such a structure to freely select the signal switching capacity thereof by suitably determining the number of segments included therein. Furthermore, a signal switching device satisfying any desired object or appli-

cation can be formed by suitably selecting the number of segments disposed along each of the X, Y and Z coordinate axes or by dividing the device structure into any suitable number of groups which are to be switchably connected via the determined numbers of inlets and outlets.

Another feature of this invention is that since all of the inlets, outlets, and interconnection means are disposed in predetermined, respective directions, connections can be established by utilizing printed circuitry, or by utilizing "tape cable" in which a plurality of parallel conductors arranged in a plane are imbedded in a tape of insulating material. This assures ease of wiring and hence, permits automatic wiring of the switching device. Furthermore, since the inlets, outlets, and interconnection means exhibit mutually orthogonal relationships, the amount of undesired crosstalk can be reduced to a minimum. In particular, since any two switching segment groups to be switchably connected are physically interconnected with linkage wires which extend in a predetermined direction, the distance between any two segment groups, as well as the crosstalk attenuation between switched information signals can be reduced to a minimum. Therefore, a signal switching device with a minimum number of switching elements can be realized as will be described.

These and other features and effects of the present invention will be apparent from the following description taken in conjunction with the accompanying drawings, wherein:

FIG. 1 is a schematic diagram illustrating the connections of a conventional signal switching device;

FIG. 2 is a transverse cross sectional view of an embodiment of a signal switching element;

FIG. 3 is a sectional view of the element taken along lines 14—14 of FIG. 2;

FIG. 4 is a graphical representation of the signal switching element;

FIG. 5 is a plan view of a first embodiment of a segment of switching elements;

FIG. 6 is a front view of the segment shown in FIG. 5;

FIG. 7 is a right side view of the segment shown in FIG. 5;

FIG. 8 is a plan view of a second embodiment of a segment of switching elements;

FIG. 9 is a front view of the segment shown in FIG. 8;

FIG. 10 is a right side view of the segment shown in FIG. 8;

FIG. 11 is a plan view of a signal switching device;

FIG. 12 is a front view of the signal switching device shown in FIG. 11;

FIG. 13 is a bottom view of the signal switching device shown in FIG. 11;

FIG. 14 is a Z-axis exploded view of a signal switching device in accordance with this invention;

FIG. 15 is a schematic diagram illustrating the connections of the signal switching device shown in FIG. 14; and

FIGS. 16 through 18 schematically show perspective views of signal switching devices in accordance with other embodiments of this invention.

Now a description will be given of a conventional signal switching device by reference to FIG. 1. As illustrated, signal switching matrices P_0 , P_1 , P_2 and P_3 , each

containing a set of 4×4 crosspoints, are provided as a primary switching stage. Matrix P_0 is comprised of inlets X_{00} , X_{01} , X_{02} , and X_{03} and outlets Y_{00} , Y_{01} , Y_{02} , and Y_{03} which intersect these inlets. Likewise, matrices P_1 , P_2 , and P_3 are comprised respectively of inlets X_{10} , X_{11} , X_{12} , X_{13} and outlets Y_{10} , Y_{11} , Y_{12} , Y_{13} ; X_{20} , X_{21} , X_{22} , X_{23} and Y_{20} , Y_{21} , Y_{22} , Y_{23} ; and X_{30} , X_{31} , X_{32} , X_{33} and Y_{30} , Y_{31} , Y_{32} , Y_{33} . Switching matrices S_0 , S_1 , S_2 , and S_3 , similar to the aforementioned primary switching stages, contain 4×4 arrays of crosspoints, and are provided as the secondary switching stage. S_0 , S_1 , S_2 , and S_3 are comprised respectively of inlets X_{00}' , X_{01}' , X_{02}' , X_{03}' , and outlets Y_{00}' , Y_{01}' , Y_{02}' , Y_{03}' ; X_{10}' , X_{11}' , X_{12}' , X_{13}' and Y_{10}' , Y_{11}' , Y_{12}' , Y_{13}' ; X_{20}' , X_{21}' , X_{22}' , X_{23}' and Y_{20}' , Y_{21}' , Y_{22}' , Y_{23}' ; and X_{30}' , X_{31}' , X_{32}' , X_{33}' and Y_{30}' , Y_{31}' , Y_{32}' , Y_{33}' .

The outlets Y_{00} , Y_{01} , Y_{02} , and Y_{03} of the primary stage switching matrix P_0 , are respectively connected to the inlets X_{00}' , X_{10}' , X_{20}' , and X_{30}' of the secondary stage switching matrices S_0 , S_1 , S_2 , and S_3 . Similarly, the outlets Y_{10} , Y_{11} , Y_{12} , and Y_{13} of the switching matrix P_1 are respectively connected to the inlets X_{01}' , X_{11}' , X_{21}' , and X_{31}' of the switching matrices S_0 , S_1 , S_2 , and S_3 . Furthermore, the outlets Y_{20} , Y_{21} , Y_{22} , and Y_{23} of the switching matrix P_2 and the outlets Y_{30} , Y_{31} , Y_{32} , and Y_{33} of the switching matrix P_3 are respectively connected to X_{02}' , X_{12}' , X_{22}' , X_{32}' , and to X_{03}' , X_{13}' , X_{23}' , X_{33}' of the switching matrices S_0 , S_1 , S_2 , and S_3 .

In each of the switching matrices P_0 , P_1 , P_2 , P_3 , S_0 , S_1 , S_2 , and S_3 , there are provided switching contacts, each capable of bridging across an inlet and an outlet, at the intersecting crosspoints of said inlets and outlets. For instance, on closure of the switching contacts identifiable as (X_{00}, Y_{00}) and (X_{00}', Y_{00}') , a signal path is established from inlet X_{00} of the primary switching stage to outlet Y_{00}' of the secondary switching stage. It has been known with such a conventional signal switching device, that a path from a desired one of the inlets X_{00} , X_{01} , X_{02} , X_{03} , X_{10} , X_{11} , X_{12} , X_{13} , X_{20} , X_{21} , X_{22} , X_{23} , X_{30} , X_{31} , X_{32} , and X_{33} to a desired one of the outlets Y_{00}' , Y_{01}' , Y_{02}' , Y_{03}' , Y_{10}' , Y_{11}' , Y_{12}' , Y_{13}' , Y_{20}' , Y_{21}' , Y_{22}' , Y_{23}' , Y_{30}' , Y_{31}' , Y_{32}' , and Y_{33}' can be established with a minimum number of switching elements. For this purpose, a switching device consisting of the illustrated switching matrices as a functional and structural unit containing a plurality of switching elements, the outlets of the primary stage switching matrices P_0 , P_1 , P_2 , and P_3 are connectable to the inlets of the secondary stage switching matrices S_0 , S_1 , S_2 , and S_3 by means of linkage wires. Consequently, in cases where these switching matrices are arranged in the same plane, the linkage wires connected between the outlets of the primary stage switching matrices P_0 , P_1 , P_2 , and P_3 and the inlets of the secondary stage switching matrices S_0 , S_1 , S_2 , and S_3 intersect one another in the same plane in a similar manner as the linkage wire between the outlet Y_{01} and the inlet X_{10}' intersects the linkage wire between the outlet Y_{10} and the inlet X_{01}' . Accordingly, it is inadvisable to use noninsulated conductors for wiring these linkage connections and further, the effort expended in wiring these points of intersection becomes extremely complex when the number of linkage wires becomes large. Furthermore, the fact that the linkage wires intersect one another in the aforescribed manner

makes it extremely difficult to limit the length of linkage wires or to reduce the space occupied by the linkage wires.

The signal switching device according to this invention is comprised of segments, the segment constituting the basic structural and functional unit, each segment containing a plurality of signal switching elements. A magnetic latching type reed switch, for example, may be used for the signal switching element. Alternatively, an electronic switch such as a transistor or a switchable ferrite core may be utilized as a switching element. The magnetic latching type reed switch may include a pair of sealed-in-glass contacts 1 and 2 disposed parallel to each other as shown in FIGS. 2 and 3, and a pair of terminals 3 and 4 disposed at opposite end portions of sealed contact 1. Similarly a pair of terminals 5 and 6 are disposed at opposite end portions of sealed contact 2. If desired, the sealed contact 2 may be omitted and the reed switch may include only a single contact 1. Plates 7 and 8 formed of magnetically semi-hard material, are disposed so as to sandwich the sealed contacts 1 and 2, and an operating coil 9 is wound about the plates 7 and 8 for controlling the direction of magnetization in these plates 7 and 8. Furthermore, a shunt plate 10 of magnetically semi-hard material is provided near the mid-point in the longitudinal direction of the sealed contacts 1 and 2, and cooperates with plates 7 and 8 to determine a magnetic path.

The operation of signal switching element 11 has been well known in the art. Therefore, a detailed description is abbreviated herein for simplicity. The symbol for the signal switching element 11 is indicated by the mark X at the point of intersection of two orthogonally intersecting conductors 12 and 13 as shown in FIG. 4. The make side and break side terminals or input and output terminals, 3 and 4, respectively, (or 5 and 6) of the signal switching element 11 correspond respectively to conductors 12 and 13.

Each segment consists of a plurality of such signal switching elements 11. For instance, as shown in FIGS. 5 through 7, the segment 15 is comprised of a rectangular parallelepiped case 16 which may be made of synthetic resin, for example, and four signal switching elements 11a, 11b, 11c, and 11d enclosed therein with respective sealed contacts aligned and in parallel relation with respect to each other. If desired, case 16 may adopt an alternative polyhedron configuration. The make side contact terminals 3a, 5a, 3b, 5b, 3c, 5c, 3d, and 5d of switching elements 11a, 11b, 11c, and 11d project respectively from the top surface 16a of the case 16. Terminals 3a, 3b, 3c, and 3d are mutually aligned and disposed parallel to mutually aligned terminals 5a, 5b, 5c, and 5d, forming an array on the top surface 16a. Similarly, break side contact terminals 4a, 6a, 4b, 6b, 4c, 6c, 4d and 6d project outward respectively from the bottom surface 16b which is parallel to the top surface 16a and are disposed in an opposite direction to that of the respective make side contact terminals. Thus, the break side contact terminals 4, 6 comprise a planar array that is parallel to and spaced from the array formed by make side contact terminals 3, 5.

Segments assuming other geometric configurations of contact terminals may also be provided such, for example, as one having an array of terminals projecting

outward from each of two adjacent orthogonal surfaces. As shown in FIGS. 8 through 10, auxiliary terminals 4a', 6a', 4b', 6b', 4c', 6c', 4d', and 6d', comprise an array disposed in the same manner as terminals 3a, 5a, 3d, and 5d, and are provided on the side surface 16c orthogonal to the case top surface 16a on which the make side contact terminals are provided and further, these auxiliary terminals are respectively connected internally by suitable conducting means to terminals 4a, 6a, 4b, 6b, 4c, 6c, 4d, and 6d. The terminals 4a through 4d and 6a through 6d are such that the spaced intervals between successive terminals are the same. The terminals 4a' through 6a' are similarly spaced. In addition, the terminals 4a-4d and 4a'-4d' are disposed along axes parallel to the axes passing through terminals 6a-6d and 6a'-6d', respectively. With this kind of segment, flangelike projections 17 and 18 are provided at opposite ends of the case 16 to form a unitary structure therewith; and two notches 19 and 20, whose width is slightly larger than the separation between the two sets of aligned terminals 3a through 3d and 5a through 5d, are provided in the flangelike projections on the top surface 16a. The projections 17 and 18 extend around the circumference of the end portion of case 16 and should be slightly higher than the height of the outwardly projecting terminals 3a-3d, 5a-5d, 4a-4d and 6a-6d. Thus, terminals 4a, 6a through 4d, 6d, to which auxiliary terminals 4a', 6a' through 4d', 6d' are connected, do not project beyond the flangelike projections 17 and 18 of the case 16 as illustrated in FIG. 10.

A simple structure of a signal switching device comprised of these kinds of segments will now be described by reference are projected FIGS. 11 through 13. According to this embodiment, four segments 15A, 15B, 15C, and 15D are mounted on a printed circuit board 22 so as to be adjacent and parallel to one another, thereby forming an array of signal switching elements. It should herein be noted that each switching element of the array may include a reed switch having a single pair of terminals such as 3,4, rather than the two pair of terminals 3,4 and 5,6 illustrated. Terminals b, is in terminal section on one surface of these segments 15A, 15B, 15C and 15D, for instance break contact terminals 4 and 6, are projected outward from the bottom surface of the printed circuit board 22 through small holes provided in the printed circuit board 22. On the bottom surface of the board 22, there are provided a conductor 23a for connection to terminals 4a of segments 15A, 15B, 15C, and 15D, a conductor 24a for connection to terminals 6a thereof, a conductor 23b for connection to terminals 4b thereof, and conductors 24b, 23c, 24c, 23d, and 24d respectively, for connection to terminals 6b, 4c, 6c, 4d, and 6d. In other words, each of the conductors 23a, 24a, 23b, 24b, 23c, 24c, 23d, and 24d is in multiple connection with the corresponding break contact terminals. The aforescribed conductors are disposed parallel to one another any may be printed on the board 22 in a conventional manner such that a portion of the board on one side constitutes a terminal section 27 on which terminals 25a, 26a, 25b, 26b, 25c, 26c, 25d, and 26d are connected to corresponding conductors. This geometrical configuration comprised of a plurality of segments and mutually interconnected with conductors so as to form an array of signal switching elements, can be con-

sidered the structural unit of a signal switching device according to this invention.

The segments 15 can be arranged not only in the one direction shown in FIGS. 11-13, but also in three-dimensional form. FIG. 14 illustrates a signal switching device comprised of four segments 15 having their long sides directed along the Z axis and stacked in the X direction, four stacks of segments disposed successively along the Y axis, and two segments disposed successively along the Z axis. The X-Y-Z directions illustrated in FIG. 14 are merely exemplary and the axes are freely interchangeable. The three-dimensional unitary structure composed of the segments can be separated into two parts along the X axis to constitute two segment groups such as a primary switching stage and a secondary switching stage, different in function and designated PSW and SSW, respectively. The former segment group PSW is comprised of a first set of segments P_{00} , P_{01} , P_{02} and P_{03} stacked in the X direction and three other sets of segments P_{10} , P_{11} , P_{12} , P_{13} , P_{20} , P_{21} , P_{22} , P_{23} , and P_{30} , and P_{31} , P_{32} , P_{33} disposed in succession in the Y direction with respect to the set of P_{00} , P_{01} , P_{02} , and P_{03} . Likewise, the latter segment group SSW is comprised of a first set of segments S_{00} , S_{10} , S_{20} , and S_{30} stacked in the X direction and three other segments S_{01} , S_{11} , S_{21} , S_{31} , S_{02} , S_{12} , S_{22} , S_{32} , S_{03} , S_{13} , S_{23} , S_{33} disposed side by side in the Y direction with respect to the set of S_{00} , S_{10} , S_{20} , and S_{30} . The latter segment group SSW is comprised of segments provided with the aforescribed auxiliary terminals. It should be understood that the number of segments utilized and the number of signal switching elements in each segment may be any convenient numbers.

On one surface of a set of segments such as the first set P_{00} , P_{01} , P_{02} , and P_{03} in the segment group PSW, i.e., on the side through which break terminals 4 and 6 for example project, a printed circuit board 22pa as described in connection with FIGS. 11 through 13 is provided. Conductors 23a, 24a, 23b, 24b, 23c, 24c, and 23d, 24d printed on the printed circuit board 22pa are aligned in the X direction respectively as inlets X_{00} , X_{01} , X_{02} , and X_{03} . In a similar position on the second set of segments P_{10} , P_{11} , P_{12} , and P_{13} , printed circuit board 22pb is provided and inlets X_{10} , X_{11} , X_{12} , and X_{13} are provided as conductors. Similarly printed circuit boards 22pc and 22pd are provided respectively for the third set of segments P_{20} , P_{21} , P_{22} , P_{23} and the fourth set of segments P_{30} , P_{31} , P_{32} , P_{33} . From these printed circuit boards 22pc and 22pd, inlets X_{20} , X_{21} , X_{22} , X_{23} and inlets X_{30} , X_{31} , X_{32} , X_{33} are respectively derived. On the surface through which make terminals 3 and 5 of the first set of segments S_{00} , S_{01} , S_{02} , and S_{03} in the segment group SSW project, a printed circuit board 22sa, similar to the one described in connection with FIGS. 11 through 13, is provided. This printed circuit board 22sa is provided with conductors 27a, 27b, 27c and 27d (not shown) respectively, in multiple connection with the make terminals 3a, 3b, 3c, and 3d associated with these segments and in addition, conductors 28a, 28b, 28c, and 28d (not shown) are provided to which the make terminals 5a, 5b, 5c, and 5d are connected, respectively. These conductors 27a, 28a, 27b, 28b, 27c, 28c, 27d, 28d are aligned in the Y direction as outlets Y'_{00} , Y'_{01} , Y'_{02} , and Y'_{03} . In like manner, printed circuit boards 22sb, 22sc, and 22sd are provided, respectively,

for segments S_{10} , S_{11} , S_{12} , S_{13} , S_{20} , S_{21} , S_{22} , S_{23} , S_{30} , S_{31} , S_{32} , and S_{33} , and these printed circuit boards 22sb, 22sc, and 22sd, are provided with conductors which comprise arrays of outlets Y'_{10} , Y'_{11} , Y'_{12} , Y'_{13} , Y'_{20} , Y'_{21} , Y'_{22} , Y'_{23} , and Y'_{30} , Y'_{31} , Y'_{32} , Y'_{33} aligned in the Y direction.

An additional printed circuit board M_{00} is provided for interconnecting the make contact terminals of the segment P_{00} and the auxiliary terminals of the segment S_{00} . The printed circuit board M_{00} is provided with a conductor 30a for connection between the make contact terminals 3 and the auxiliary terminals 4', and a conductor 31a is provided for connection between the make contact terminals 5 and the auxiliary terminals 6'. These conductors 30a and 31a constitute a linkage wire L_{00} extending in the Z direction. In a similar manner, a printed circuit board M_{01} is provided so as to interconnect the make contact terminals of the segment P_{01} and the auxiliary terminals of segment S_{10} , and on this board M_{01} a linkage wire L_{01} is provided. Likewise, printed circuit boards M_{02} , M_{03} , M_{10} , M_{11} , M_{12} , M_{13} , M_{20} , M_{21} , M_{22} , M_{23} , M_{30} , M_{31} , M_{32} , and M_{33} are respectively provided so as to cover the full lengths of paired segments P_{02} and S_{20} , and P_{03} , and S_{30} , P_{10} , and S_{01} , P_{11} , and S_{11} , P_{12} and S_{21} , P_{13} and S_{31} , P_{20} and S_{02} , S_{02} , P_{21} and S_{12} , P_{22} and S_{22} , P_{23} and S_{32} , P_{30} and S_{03} , P_{31} and S_{13} , P_{32} and S_{23} , and P_{33} and S_{33} and further, the linkage wires L_{02} , L_{03} , L_{10} , L_{11} , L_{12} , L_{13} , L_{20} , L_{21} , L_{22} , L_{23} , L_{30} , L_{31} , L_{32} , and L_{33} are respectively aligned on these printed circuit boards.

The segment groups PSW and SSW have been separated from each other in the illustration of FIG. 14 merely for ease of understanding, but actually they are united to form a unitary structure. Furthermore, all of the above-mentioned printed circuit boards M are understood to be provided although most of them are not shown in the illustration.

FIG. 15 is a schematic diagram illustrating the connections of the signal switching device of FIG. 14, wherein single lines are used to indicate the interconnections between pairs of segments P_{00} , and S_{00} , P_{01} and S_{10} , P_{02} and S_{20} , and P_{03} and S_{30} , although pairs of interconnections may be used. Similar interconnecting relationships for segments P_{10} and S_{01} , P_{11} and S_{11} , P_{12} and S_{21} , P_{13} and S_{31} , and so forth are also illustrated in FIG. 15. Consequently, the signal switching device of FIG. 14 will become a 16×16 matrix with 16 inlets (X_{00} . . . X_{33}) and 16 outlets (Y'_{00} . . . Y'_{33}) as a whole as will be apparent from the corresponding illustration of FIG. 15. As will be evident from a comparison between FIG. 15 and FIG. 1, or from an inspection of FIG. 14, the inlets X'_{10} , X'_{20} , and X'_{30} of each of the secondary stage switches S_1 , S_2 , and S_3 in FIG. 1 have been rearranged on the linear extension of the outlets Y_{01} , Y_{02} and Y_{03} of the primary stage switch P_0 but the electrical connections have been maintained. Further, the inlets X'_{01} , X'_{21} , and X'_{31} of each of the secondary stage switches S_0 , S_2 , and S_3 of FIG. 1 have been rearranged on the linear extension of the outlets Y_{10} , Y_{12} , and Y_{13} of the primary stage switch P_1 while maintaining the original electrical connections. Similarly, the inlets of each of the secondary stage switches S_0 , S_1 , S_2 , and S_3 , have been rearranged on the linear extension of the outlets of each of the primary stage switches P_2 and P_3 . Thus, it is seen the signal switching device of FIG. 14 performs

an operation equivalent to the conventional device shown in FIG. 1 and admits of ready application with digital computers, data processing equipment, communication switching equipment and the like.

With the signal switching device according to this invention shown in FIG. 14, the inlets X_{00} through X_{33} are disposed in parallel relation to one another, as are the interconnection means L_{00} through L_{33} and the outlets Y'_{00} through Y'_{33} . It will be seen from this embodiment that the inlets, interconnection means and outlets can be formed on respective printed circuit boards. This permits ease of automatic connections for the inlets, the outlets, the interconnection means, and their associated terminals. All of the segments of the segment group PSW are geometrically aligned with the corresponding segments of the group SSW. Accordingly, the interconnection means L_{00} through L_{33} which correspond to the linkage wires of the conventional device shown in FIG. 1 are integrated into the unitary structure of PSW and SSW, such that these interconnections can be established in a single operation. With the conventional device shown in FIG. 1, plural connecting steps were necessary, because the outlets of the primary stage switches which were connected to crosspoint terminals and the inlets of the secondary stage switches which were connected to crosspoint terminals had to be further connected with linkage wires to establish interconnection between the inlets and the outlets.

It will be obvious from the foregoing that the switching capacity of a signal switching device can be readily controlled by increasing or decreasing the number of segments in the X or Y direction or both directions, of either or both of segment groups PSW or SSW as illustratively presented in FIG. 14. For example, at a segment group PSW a switching matrix of 32×16 crosspoints can be realized by adding still another segment group PSW' (not shown) in Z direction and corresponding linkage wires ($L_{00} \dots L_{33}$) for extending the necessary connections.

It is seen that the inlets X_{00} through X_{33} , the outlets Y'_{00} through Y'_{33} , and the interconnection means L_{00} through L_{33} extend respectively along the X, Y, and Z axes. Since these conductors intersect substantially at right angles, noise signals due to mutual inductance therebetween are suppressed to a minimum and the amount of crosstalk is greatly reduced. Moreover, the segment groups PSW and SSW can be physically positioned in close proximity such that the linkage wires share no points of intersection. This assures excellent electrical transmission characteristics such as low transmission loss, improved crosstalk attenuation response, and wider operating frequency bandwidth.

Although not shown in FIG. 14, the printed circuit boards 22pa through 22pd and 22sa through 22sd can be mounted in a support frame by inserting opposite edges of each board into pairs of guide slots provided in the support frame whereby the relative positions of the segments in the illustrated segment groups remain as shown. In this case, the terminal sections 27 of the printed circuit boards can be plugged into multi-lead jacks provided in the support frame so as to permit connections with other equipment.

The device shown in FIG. 14 is composed of a plurality of segment units, each unit comprised of four segments. Such a segment unit can also be represented as a

basic structural unit of the switching device. While a particular embodiment is illustrated in FIG. 14, in which printed circuit boards are used for terminal connections of the inlets, outlets, and interconnection means, conventional tape cable may be utilized in another embodiment. The tape cable consists of a thin, flexible film of insulating material and a plurality of parallel conductors laid on or imbedded in the film along the longitudinal direction thereof. An embodiment of a signal switching device using the tape cable is illustrated in FIG. 16. As illustrated therein, the printed circuit boards 22pa through 22pc and 22sa through 22sc of FIG. 14 are replaced with tape cables denoted by corresponding reference characters 33pa through 33pc and 33sa through 33sc. Conductors 30 and 31 are directly connected as by wires without using interconnection means such as the printed circuit boards M_{00} through M_{22} , and segments provided with flangelike projections 17 and 18 as previously illustrated in FIGS. 8 through 10 are employed.

Although a switching device comprised of two segment groups has thus far been described, it is contemplated that more than two segment groups may comprise a unitary switching device. For instance, an embodiment shown in FIG. 17 illustrates a switching device divisible into two parts along the X axis, the lower part of the structure is divisible into two segment groups 40 and 41 along the Y axis and further, the upper part is divisible into two segment groups 42 and 43 along the Z axis. Furthermore, the divisibility of a switching device by a single plane is by no means a limiting condition. This invention encompasses the possibility of dividing a switching device into a plurality of parts by a combination of planes 45, 45', 45'' . . . which intersect orthogonally to one another to form segment groups 46 and 47 as illustrated in FIG. 18.

Thus, it is seen, the structures contemplated by this invention consist generally of l , m , and n segments disposed in succession along X, Y, and Z rectangular coordinate axes, each segment containing a plurality of switching elements. Each of l , m , and n should be a positive integer equal to or larger than unity, and at least one of them should be equal to or larger than 2. Furthermore, the switching device may be divided into a plurality of segment groups and when any two groups are taken into consideration, inlets are derived from one group in a first direction, such as for example, the X direction, outlets are derived from the other group in a second direction, orthogonal to the first, such as the Y direction, and interconnection means for connecting the two groups are derived in a third direction, orthogonal to said first and second directions, such as the Z direction. The numbers of inlets, outlets, and interconnection means are, respectively, a , b , and c (each of them being a positive integer equal to or larger than unity), and are in multiple connection with the terminals of the switching elements included in the segments. Although the invention has been described with particular reference to a switching element comprised of a magnetic latching type reed switch, it will be evident that any other suitable element such as a semiconductor switching element, a ferrite core, or the like may be used. If a reed switch is adopted, it may include a single make terminal and a single break ter-

rninal, or a plurality of make and break terminals as hereinbefore described.

What is claimed is:

1. A signal switching device, comprising:

a plurality of each of first and second groups of 5 rectangular parallelopiped switching units arranged in X, Y and Z directions;

each of said first groups having said units thereof arranged in stacks in said X direction with respective lengthwise axes positioned in parallel in said Z direction; said first unit group stacks disposed side-by-side in said Y direction;

each of said second groups having said units thereof arranged in stacks in said X direction with respective lengthwise axes positioned in parallel in said Z direction; said second unit group stacks disposed side-by-side in said Y direction;

each of said first group units including a plurality of pairs of switches disposed lengthwise of each of said last-mentioned units; each of said switches having a make terminal and a break terminal; each of said unit switches of said first group disposing said make terminals on one side of each of said last-mentioned units and said break terminals on a 25 side of each of said last-mentioned units opposite to said one side; whereby said first group units stacked and disposed in said respective X and Y directions position said make and break terminals in alternate parallel X-Z planes;

each of said second group units including a plurality of pairs of switches disposed lengthwise of each of said last-mentioned units; each of said second group switches having a make terminal and an auxiliary break terminal; each of said unit switches of 30

said second group disposing said make terminals on one side of each of said last-mentioned units and said auxiliary break terminals on a side orthogonal to said last-mentioned one side; whereby said second group units stacked and disposed in said respective X and Y directions position said auxiliary break terminals in spaced parallel X-Z planes and said make terminals in spaced parallel Y-Z planes;

a plurality of pairs of spaced parallel conductors disposed in the Z direction for multiple connecting said make terminals of said first group switch units and corresponding auxiliary break terminals of said second group switch units in said X-Z planes; a plurality of first groups of spaced parallel conductors disposed in said X direction in said respective spaced X-Z planes of said first group units for multiply connecting of said break terminals of corresponding switches in said respective first group unit stacks;

a plurality of second groups of spaced parallel conductors disposed in said Y direction in said respective Y-Z planes for multiply connecting said make terminals of corresponding switches of said second group units in said Y-Z planes;

input signal lines disposed in parallel and connected to said break terminals of said switches in said respective first group units in said X-Z planes; and output signal lines disposed in parallel and selectively connected to said make terminals of said switches of said second group units in said Y-Z planes; whereby a desired one of said input signal lines is connectable to a desired one of said output lines.
